UNITED STATES PATENT OFFICE.

REUBEN D. ROBINSON, OF GRAND RAPIDS, MICHIGAN.

ELECTRIC LAMP.

Application filed November 16, 1923. Serial No. 675,031.

To all whom it may concern:

Be it known that I, REUBEN D. ROBINSON, a citizen of the United States, residing at Grand Rapids, in the county of Kent and State of Michigan, have invented new and useful Improvements in Electric Lamps, of which the following is a specification.

The present invention relates to electric lamps; and its object is to provide in such a lamp a plurality of electric-light-producing elements with improved means between them for preventing the light from one or more thereof from shining in the same direction in which the light from another one or more of said elements shines.

This and any other objects hereinafter appearing are attained by, and the invention finds preferable embodiment in, the electric lamp hereinafter particularly described in the body of this specification and illustrated by the accompanying drawings, in which:

Figure 1 is a right hand side view of an electric lamp with a parabolic reflector which is shown in vertical central section;

Figure 2 is a right hand side view of said lamp (enlarged), the light-shield thereof being shown in vertical longitudinal section;

Figure 3 is a front view of the same, the light-shield being shown in vertical transverse section taken on line 3-3 of Figure 2;

Figure 4 is a top plan view of the light-shield and one of the light-producing elements; and

Figure 5 is a right-hand side of the light-shield and of the light-producing elements; and showing another method of supporting the light-shield.

In the construction illustrated by the drawings, an electric lamp, adapted for use as an automobile lamp is shown, having a translucent (glass) globe or bulb 1 supported by its mounting member 2 at its rear and located in the parabolic reflector 3. The principal illuminating or light-producing element is shown in the form of a filament 4 electrically supplied by the lead-in wires 5, 6 in the lamp's glass plug 7. This principal light-producing element is located at the focus of the parabolic reflector so that the rays of light therefrom may shine parallelly forward as indicated in Figure 1.

A second illuminating or light-producing

element is shown in the form of a filament 9 located in the bulb and between its rear end and the light-element or filament 4, i. e., behind said filament, its purpose being to function as a "dimmer" light. This second element is electrically supplied by the lead-in wires 10 and 5 having a branch wire 11. It will be seen that only three of these lead-in wires extending through the lamp's glass plug 7 are employed to electrically supply both the light-producing elements or filaments 4 and 9. In order to prevent the light from the second light-producing element 9 from shining forwardly, a light-shield 12 is positioned between the two elements 4 and 9; and in order to prevent the light from this second element 9 from shining upwardly, the light-shield extends at 13 horizontally above this element; and to prevent the light therefrom from shining laterally, said light-shield extends downwardly at 14, 14 on the sides of said element.

This light-shield may be supported inside the bulb 1 by means of a rod 15 anchored in the glass plug 7 as seen in Figure 5; or by rods 16, 17 connected to the lead-in wires 5, 10 as seen in the other views, in which case, one or both of these rods 16, 17 must be of insulating material.

The lower surface of portion 13 of the light-shield may be light-reflecting so as to reflect the light from element 9 downwardly.

The invention being intended to be pointed out in the claims, is not to be limited to or by details of construction of the particular embodiment or embodiments thereof illustrated by the drawings or hereinbefore shown or described.

I claim:

1. In an electric lamp: a translucent globe; an electric-light-producing element within the globe; a second electric-light-producing element within the globe and between said first-mentioned element and the rear of the globe; an opaque light-shield extending between said elements to prevent the light from said second-mentioned element from shining forwardly but permitting it to shine downwardly, the light from said first-mentioned element shining forwardly, upwardly and downwardly; means for electro-energizing said elements separately.
2. In an electric lamp: a translucent globe;

an electric-light-producing element within the globe; a second electric-light-producing element within the globe and between said first-mentioned element and the rear of the globe; an opaque light-shield extending between said elements and above said second-mentioned element to prevent the light from said second-mentioned element from shining forwardly and upwardly but permitting it to shine downwardly, the light from said first-mentioned element shining forwardly, upwardly and downwardly; means for electro-energizing said elements separately.

3. In an electric lamp: a translucent globe; an electric-light-producing element within the globe; a second electric-light-producing element within the globe and between said first-mentioned element and the rear of the globe; an opaque light-shield extending between said elements and above said second-mentioned element and laterally thereto to prevent the light from said second-mentioned element from shining forwardly, upwardly and laterally but per-

mitting it to shine downwardly, the light 25 from said first-mentioned element shining forwardly, upwardly and downwardly; means for electro-energizing said elements separately.

4. In an electric lamp: a translucent 30 globe; an electric-light-producing element within the globe; a second electric-light-producing element within the globe and between the first-mentioned element and the rear of the globe; a light-shield extending 35 between said elements and above said second-mentioned element and having a light-reflecting lower surface, to prevent the light from said second-mentioned element from shining forwardly and for reflecting the 40 same downwardly, the light from said first-mentioned element shining forwardly, upwardly and downwardly; means for electro-energizing said elements separately.

In testimony whereof I have hereunto set 45 my hand at Grand Rapids, Michigan, this 12th day of November, 1923.

REUBEN D. ROBINSON.
